UNITED STATES PATENT OFFICE.

MELVIN A. YEAKLEY, OF CANTON, OHIO, ASSIGNOR TO JOHN E. McLAIN, OF CANTON, OHIO.

TROLLEY-CATCHER.

1,146,835.

Specification of Letters Patent. Patented July 20, 1915.

Original application filed June 1, 1908, Serial No. 436,147. Divided and this application filed December 30, 1913. Serial No. 809,482.

To all whom it may concern:

Be it known that I, MELVIN A. YEAKLEY, a citizen of the United States, residing at Canton, in the county of Stark and State of Ohio, have invented certain new and useful Improvements in and Relating to Trolley-Catchers, of which the following is a specification.

This invention relates to means for maintaining a trolley rope taut as the trolley end of the trolley pole moves up and down to adapt itself to different heights of the wire, and to catch and hold the paying out device for the trolley rope when such paying out becomes unduly rapid as when the trolley jumps the wire. Such means are commonly known as trolley catchers.

To prevent the unduly rapid paying out of the trolley rope, it has heretofore been largely the practice to provide dogs which, upon the too rapid movement of the rope drum, would rigidly lock the drum to a stationary portion or stop. More specifically, the structure has comprised a drum for the trolley rope upon which are mounted centrifugal dogs which, upon undue speed of the drum, fly outwardly and engage projections or teeth upon the inside of the casing. The means described result in an abrupt stop thereby severely shocking and straining the parts with the likelihood of causing breakage. Particularly is there a liability of breaking the teeth upon the casing, and where these teeth are integral with the casing, as is almost universally the practice, their breakage necessitates the provision of a new casing.

It is an object of my invention to obviate the disadvantages noted in devices of this character and to this end a yielding device at all times active is included in the means for stopping the winding drum, whereby the impact of the parts is cushioned. This yielding device may be located at any suitable point of the stopping means and may consist of a spring, a friction device or other suitable means which will permit a "give" of the parts upon the stoppage of the drum and at the instant of engagement of the elements for stopping the drum's rotation.

In the embodiment of the invention which has been chosen to illustrate it, and which is shown in the accompanying drawings, the yielding device is shown as a normally ac-

tive coiled spring, so that upon operation 55 of the dog, the spring will prevent the abrupt stoppage of the drum.

Another object of my invention is to provide means which tend to retain the centrifugal stop dog in contact with a stop in the mechanism when said dog has been thrown out by centrifugal force into engagement with said stop to check the upward travel of the trolley pole; so that thereafter, in the event the trolley pole rebounds or is moved downwardly for any reason, the attendant rewinding of the trolley rope on the rope drum, under the action of the slack-absorbing spring, will be accompanied by an effort on the part of said means to retain the 70 stop dog in the path of said stop. This being the case, when the rebound of the trolley pole or its said downward travel is completed and the pole again starts to move upwardly, the centrifugal stop dog will instantly engage the stop and prevent the further upward travel of the trolley pole.

With these and other objects in view, the invention consists of the parts and combinations of parts hereinafter described and set forth in the appended claims.

This application is a division of my application filed June 1st, 1908, Serial No. 436,147.

For the purpose of illustrating my invention, I have selected and hereinafter described one construction embodying it.

Figure 1 is a vertical sectional view of an apparatus embodying my invention, the view being on the line 1-1 of Fig. 2. Fig. 2 is a section on the line 2-2 of Fig. 1. Fig. 3 is a section partly on the line 3-3 and partly on the line 3'-3' of Fig. 1. Fig. 4 is a perspective view of the ratchet carrying member. Fig. 5 is a sectional view 95 through the drum illustrating the manner of connecting the trolley rope thereto and the devices which lock the drum against rotation upon disconnection of the rope.

Referring to the drawings, the casing is 100 divided vertically and the two halves 1 and 2 are held together by a bolt 3 which also serves as an axle for the interior mechanism. When assembled the casing has an opening 4 through which the trolley rope 5 passes 105 and there is an opening 6 beneath the winding drum 7. The winding drum 7 is journaled on the bolt 3. At 1' the casing mem-

ber 1 is provided with an inwardly extending flange which, with the adjacent walls of the casing member 1 forms a circular groove 50 extending concentrically to the 5 axis of the bolt 3.

48, 49 indicate abutments arranged in and transversely of the groove 50. The abutments 48, 49 are preferably formed integrally with the casing member 1, and extend 10 inwardly from diametrically opposite sides thereof. The purpose of the groove 50 and abutments 48, 49, will be later described.

Upon one side or face of the drum 7 are mounted pins 10 and 11 on opposite sides of 15 its center. Upon these are respectively pivoted the centrifugal dog 12 and its counterweight 13. The dog and counterweight are connected by a spring link 14; and a spring 15, coiled about the pin 10 and engaging at 20 one end with the dog 12 and at the other end with the drum 7, tends to hold the dog 12 out of engagement with the teeth 45 of a member 44 to be later described.

Upon undue speed the force of the spring 25 will be overcome and the dog will engage with the ratchet teeth. The utility of the counterweight will be apparent when it is considered that the bolt 3 is horizontal and that therefore in the position shown (see 30 Fig. 2) the weight of the dog opposes the centrifugal force. When the dog-carrying member has turned through 180 degrees and the dog occupies the position shown in the drawing as occupied by the counterweight, the weight of the dog will be added to the centrifugal force in producing a tendency for it to move outward. With the counterweight and the dog linked together, as shown, their weights are balanced at all times so that gravity has no influence upon the dog, which responds solely to the centrifugal force. The counterweight might also be adapted to act as a dog but ordinarily one dog will prove sufficient. 45 The link 14, being of spring material, the parts are not hampered in their movements as would be the case if this link were rigid.

The spring 26 is for turning the drum 7 to maintain the trolley rope taut as the trolley adapts itself to varying heights of the trolley wire. This spring engages at one end with the hub of the winding drum 7 and at the other end is secured to a segmental spring 27 which rests upon the interior of 50 the casing. The engagement of one end of the spring 26 with the hub of the winding drum 7 is preferably accomplished by bending the end of the spring into a recess as is clearly shown in Fig. 3. The side of this 55 recess against which the bent end of the spring is drawn when the spring is wound is at a somewhat abrupt angle with the bottom of the recess so that movement of the end of the spring in this direction is arrested. The other side of the recess, how-

ever, is a gradual incline, as shown, so that if the parts are turned to unwind the spring, the end of the spring will slide out of the recess and about the hub, thereby preventing breakage of the spring in case an attempt is made to wind it in the wrong direction. The manner of securing the other end of the spring, namely, by means of the segmental spring 27 sliding upon the interior of the casing, prevents the too tight winding of the spring. If an attempt is made to wind the spring beyond a certain tension, the segment 27 will slide and prevent it. In some circumstances the friction between the segment 27 and a smooth casing interior 75 might be sufficient, but it is preferred to provide teeth 28 as shown upon the casing in the recesses between which the projection 29 upon the segment 27 extends. Upon a too tight winding of the spring, this projection will be withdrawn from the recess in which it may be located and the segment 80 will slide about the interior of the casing and relieve the surplus tension.

Encircling the bolt 3 is a plate 18 having 90 a ratchet 19 upon its hub. The hub of the plate 18 is preferably loosely sleeved over a reduced portion of the hub for the drum 7. The plate 18 and its ratchet are held against rotation by means of a projection 20 which 95 projects into a recess 21 in the casing. Pivoted at 22 upon the winding drum is a pawl 23, having its nose normally held in engagement with the ratchet 19 by means of a spring 24 which is coiled about the pivot 22 100 and has one end in engagement with the drum 7 while the other end is in engagement with the tail of the pawl, as shown. The tail of the pawl extends over a hole 25 in the drum. This hole is key-hole shaped, that is, is wider at one end than at the other (the wide end being at the right hand in Fig. 5). The knotted end of the trolley rope may be passed through the wide portion of the hole 25 and the rope being then 105 drawn into the narrow portion after the knot has been passed within the drum, the end of the rope is securely fastened to the drum by reason of the fact that the knot cannot pass through the narrow portion of the hole. Furthermore, the knot operates to elevate the tail end of the pawl thereby 110 throwing its nose out of engagement with the ratchet 19.

The tooth or ratchet carrying member 44 115 is arranged intermediate the drum 7 and outer wall of the casing member 1. It comprises a ring 44' having a wall 44^a that is formed with a bearing opening 44^b to receive the shaft 3, whereby the ring is loosely mounted thereon. At 45 the ring 44' is provided with an internal ratchet with which the centrifugal dog 12 is adapted to engage.

46, 47 indicate projections extending radially from diametrically opposite sides of 120

the member 44, and arranged in the plane of the abutments or stops 48, 49, on the casing member 1.

51 indicates a yieldable device, preferably 5 a coiled spring, arranged in the groove 50 at one side of the stop 48 and between it and the projection 46 on the intermediate member 44. The spring 51 may be of less length than the distance between the stop 10 48 and projection 46 when the intermediate member 44 is in normal position, as shown in Fig. 2. The cushion spring 51 is adapted to buff or cushion the blow between the intermediate member 44 and the casing 1 15 when the dog 12 under the unduly rapid rotation of the drum 7 engages a tooth on the ratchet 45 and rotates the intermediate member 44. The stoppage of the upward travel of the trolley pole under such conditions is effected with the cushioning action 20 of the spring 51 between the casing 1 and the projection 46 on the intermediate member 44.

52 indicates a flexible device for maintaining the stopping means in operative relation or in engagement with each other during the rebound of the trolley pole after it has been arrested thereby. The device 52 preferably comprises a light, relatively weak 25 coiled spring arranged in the groove 50 and between the projection 47 on the intermediate member 44 and the stop 49. The spring 52 engages the projection 47 and stop 49 at its opposite ends and normally 30 tends to maintain the intermediate member in the position shown in Fig. 2, that is, with the projection 47 in engagement with the stop 48 and the projection 46 in engagement with the stop 49.

40 As a result of the stopping of the trolley pole due to engagement of the dog 12 with the teeth 45, the trolley pole may rebound slightly and cause slack in the rope 5. During this rebound, the spring 26 exerting 45 its influence upon the drum 7, rotates said drum in anti-clockwise direction to take up the rope slack. As the spring 52 has been compressed between the stop 49 and projection 47, it acts upon the latter in an anti-clockwise direction and thus tends to rotate or exert a pressure on the member 44 anti-clockwise, the effect of which is to maintain the dog 12 in operative position relative to the ratchet tooth it engaged to stop clockwise rotation of the drum 7. It will thus 50 be seen that the stoppage means will remain in condition to immediately stop clockwise rotation of the drum during the rebound of the trolley pole, so that when the trolley pole again swings upwardly it will 55 be arrested at once. The rebound of the trolley pole occupies such a short interval of time that the dog 12, owing to the action of the spring 52 upon the member 44, is not moved materially, if at all, from the path

of the ratchet tooth and is therefore ready to engage the ratchet tooth before or the instant the pole starts upwardly after the rebound. Furthermore, when the trolley has left the overhead conductor and the 70 trolley pole has been stopped by the action of the catcher from further upward travel of the trolley, should the said pole engage with a span wire, or any superstructure for the overhead conductor and have its 75 trolley end forced downwardly, the winding drum 7 will instantly and freely act to wind up the trolley rope slack and when the said trolley pole is again free to swing upwardly at its trolley end, such movement will be immediately stopped by the engagement of the dog 12 with the ratchet 45, which has been retained in readiness for instant stoppage action. In this construction the spring 52 is made very light and thin, it being intended for the purpose of exerting pressure on the member 44 to rotate it, whereby the centrifugal dog 12 is retained in the path of the ratchet 45 during the winding up action of the drum 7; when a rebound of 80 the trolley pole occurs, thus adapting the operation of the centrifugal dog to act substantially instantly after the rebound of the trolley pole, following the action of the device in stopping the upward travel of 85 the said pole. As the spring 52 is interposed between the intermediate member 44 and casing and is compressed by the action of the drum stopping means, it serves as auxiliary means to the spring 51 in cushioning 90 the impact of the dog 12, when engaging the ratchet 45. For this purpose I have found it advantageous to so make and hold the spring 52 in the casing 1, that its compression will require several times the power 95 that the spring will deliver when expanding, that is, the spring 52 is intended to be strong enough or to have expansion force sufficient only to maintain the dog 12 in engagement with a ratchet tooth, but to 100 be so arranged and constricted as to assist the spring 51 in yieldingly arresting the unwinding of the trolley cord.

In the device illustrated, I have shown that portion of the groove 50 in which the 105 said spring is arranged, to taper in diameter from the stop 48 to the stop 49, so that the compression of the spring 52 must be effected against the frictional resistance of the walls of said groove 52 to the compression 110 of the said spring therewith, while the spring is free to expand from the stop 49 toward the stop 48.

Any suitable means may be provided for 115 securing the apparatus to a car, one example 120 of such means being indicated as an entirety at 30.

In the operation of the catcher, assuming 125 that the slack-absorbing spring 26 is unwound, possibly the simplest manner of 130

winding it up and placing the catcher in condition for operation, is to loop a section of the trolley rope around the drum 7, then holding the respective ends of the loop firmly in either hand, to seesaw the rope back and forth around the drum, bearing against the periphery of the drum when pulling in the direction to wind the said spring 26, and easing up when pulling in the reverse direction. This is continued until a clattering or chattering noise is heard which indicates that the segment 27 is slipping about the interior of the casing. The loop of the trolley rope is then withdrawn from the catcher and the lower knotted end of it is introduced through the rope opening 25 and the cord is drawn back into the narrow part of said opening so as to throw the said knotted end against the free end or tail of the pawl simultaneously swinging the nose of the pawl out of engagement with the ratchet 19 and releasing the drum and its slack absorbing spring; the latter then acts to rotate the drum and wind up the desired amount of trolley rope upon the drum.

When the catcher is not in use and the trolley rope is removed, the spring 26 would quickly unwind, necessitating rewinding before it could be placed in use, unless means were provided for preventing it. In the apparatus shown, when the knot of the trolley rope is removed from the hole 25 the nose of the pawl 23 is thrown into engagement with the stationary ratchet 19 so that the spring is prevented from unwinding. When, however, the catcher is placed in service, the pawl 23 is removed from the ratchet 19 upon the insertion of the knot of the trolley rope beneath the tail of the pawl, then the drum is free to move under the action of the spring and maintain the trolley rope taut under the raising and lowering of the trolley in adapting itself to varying heights of the trolley wire. If, however, the trolley should leave the wire the drum would rotate at such a rate that the dog 12 would fly outwardly into engagement with the ratchet 45, whereupon the drum would be stopped and the trolley caught.

To those skilled in the art of making apparatus of the class described, many alterations in construction and widely differing embodiments and applications of my invention will suggest themselves, without departing from the spirit and scope thereof. My disclosures and the description herein are purely illustrative, and are not intended to be in any sense limiting.

What I claim is:

1. In mechanism of the class described, the combination of a drum, means for rotating said drum in one direction, devices having connection with said drum for yieldingly stopping the rotation of the drum when the trolley pole swings upwardly, and

auxiliary means coöperating with said stopping devices for stopping the rotation of the drum.

2. In mechanism of the class described, the combination of a drum, means for rotating said drum in one direction, devices, having connection with said drum for yieldingly stopping the rotation of the drum when the trolley pole swings upwardly, and normally active auxiliary means coöperating with said devices for stopping the rotation of the drum.

3. In mechanism of the class described, the combination with a casing, of a drum, means for rotating said drum in one direction to wind the rope thereon, means interposed between said drum and casing for stopping the rotation of the drum in rope paying out direction, and normally active means for maintaining the stopping means in operative relationship during rebound of the trolley pole.

4. In mechanism of the class described, the combination of a drum, means for rotating said drum in one direction, devices having connection with said drum for stopping the rotation of the drum when the trolley pole swings upwardly, and auxiliary means coöperating with said stopping devices for stopping the rotation of the drum, the said auxiliary means operating to maintain the stopping devices in engagement during the rebound of the trolley pole.

5. In mechanism of the class described, the combination of a drum, means for rotating said drum in one direction, devices having connection with said drum for yieldingly stopping the rotation of the drum when the trolley pole swings upwardly, and means for maintaining the stopping means in engagement during the rebound of the trolley pole.

6. In mechanism of the class described, the combination with a casing, of a drum, means for rotating said drum in one direction to wind the rope thereon, and means interposed between said drum and casing for stopping the rotation of the drum in rope paying out direction, the said means including a rotatable member provided with ratchet teeth, a centrifugal pawl carried by the drum and arranged to engage said ratchet teeth and a spring interposed between said member and the casing for cushioning the impact of the pawl when engaging said ratchet, and means acting on said member for maintaining the stopping means in operative relationship during rebound of the trolley pole.

7. In mechanism of the class described, the combination with a casing, of a drum, means for rotating said drum in one direction to wind the rope thereon, and means interposed between said drum and casing for stopping the rotation of the drum in rope paying out direction, the said means includ-

ing a rotatable member provided with ratchet teeth, a centrifugal pawl carried by the drum and arranged to engage said ratchet teeth and a spring interposed between said member and the casing for cushioning the impact of the pawl when engaging said ratchet.

8. In mechanism of the class described, the combination with a casing, of a drum, means for rotating said drum in one direction to wind the rope thereon, means interposed between said drum and casing for stopping the rotation of the drum in rope paying out direction, the said means including a rotatable member provided with ratchet teeth, a centrifugal pawl carried by the drum and arranged to engage said ratchet teeth, and a spring interposed between said member and the casing for cushioning the impact of the pawl when engaging said ratchet, and yieldable means acting on said member for maintaining the stopping means in operative relationship during rebound of the trolley pole.

25 9. In mechanism of the class described, the combination with a casing having an abutment, of a drum, means for rotating said drum in one direction to wind the rope thereon, and means interposed between said drum and casing for stopping the rotation of the drum in rope paying out direction, the said means including a rotatable member provided with internal ratchet teeth and a projection, a centrifugal pawl carried by
30 the drum and arranged to engage the ratchet and a spring interposed between said projection and said abutment for cushioning the impact of the pawl when engaging said ratchet.

40 10. In mechanism of the class described, the combination with a casing having an abutment, of a drum, means for rotating said drum in one direction to wind the rope thereon, means interposed between said 45 drum and casing for stopping the rotation of the drum in rope paying out direction, the said means including a rotatable member provided with internal ratchet teeth and a projection, a centrifugal pawl carried by the drum and arranged to engage the ratchet and a spring interposed between said projection and said abutment for cushioning the impact of the pawl when engaging said ratchet, and means acting on said member 50 for maintaining the stopping means in operative relationship during rebound of the trolley pole.

11. In mechanism of the class described, the combination with a casing provided with an abutment, of a drum, means for rotating said drum in one direction to wind the rope thereon, means interposed between said drum and casing for stopping the rotation of the drum in rope paying out direction, the said means including a rotatable

member provided with internal ratchet teeth and a projection; a centrifugal pawl carried by the drum and arranged to engage the ratchet and a spring interposed between said projection and said abutment for cushioning the impact of the pawl when engaging said ratchet, and means acting on said member for maintaining the stopping means in operative relationship during rebound of the trolley pole, the said stop-maintaining means being placed under tension by the stoppage of the drum. 7

12. In mechanism of the class described, the combination with a casing having a pair of spaced abutments, of a drum, means for rotating the drum in one direction to wind the trolley rope thereon, a rotatable member having a ratchet and a pair of spaced projections, a centrifugal pawl carried by the drum and arranged to engage the ratchet on said member, a spring interposed between one of the casing abutments and one of said projections on said member for cushioning the impact of said pawl when engaging the ratchet, and a spring interposed between the other casing abutment and the other projection for maintaining the pawl in engagement with the ratchet during rebound of the trolley pole.

13. In mechanism of the class described, 9
the combination of a casing formed with an
annular groove and provided with a pair of
spaced abutments arranged in said groove, a
rotatable drum on which the trolley rope is
wound, means for rotating the drum in one
direction, a centrifugal pawl carried by the
drum, a rotatable member provided with a
ratchet arranged to be engaged by said pawl
when the drum rotates at high speed and a
pair of spaced projections, and a pair of coiled
springs mounted in the groove, each spring
being arranged between one of said abut-
ments and one of said projections, one of
said springs acting to cushion the impact
of the pawl when engaging the ratchet and
the other spring acting to maintain the pawl
and ratchet in engagement during rebound
of the trolley pole. 1

14. In mechanism of the class described, the combination of a casing formed with an annular groove and provided with a pair of spaced abutments arranged in said groove, a rotatable drum on which the trolley rope is wound, means for rotating the drum in one direction, a centrifugal pawl carried by the drum, a rotatable member provided with a ratchet arranged to be engaged by said pawl when the drum rotates at high speed and a pair of spaced projections, and a pair of coiled springs mounted in the groove, each spring being arranged between one of said abutments and one of said projections, one of said springs acting to cushion the impact of the pawl when engaging the ratchet and the other spring acting to maintain the pawl and

- ratchet in engagement during rebound of the trolley pole, the walls of the casing forming the groove for the pawl and ratchet maintaining spring being tapered.
- 5 15. In mechanism of the class described, the combination of a casing formed with an annular groove and provided with a pair of spaced abutments arranged in said groove, a rotatable drum on which the trolley rope is wound, means for rotating the drum in one direction, a centrifugal pawl carried by the drum, a rotatable member provided with a ratchet arranged to be engaged by said pawl when the drum rotates 10 at high speed and a pair of spaced projections, and a pair of coiled springs mounted in the groove, each spring being arranged between one of said abutments and one of said projections and operating to cushion 15 20 the impact of the pawl when engaging the ratchet.
16. In mechanism of the class described, the combination of a casing formed with an annular groove and provided with a pair of spaced abutments arranged in said groove, a rotatable drum on which the trolley rope is wound, means for rotating the drum in one direction, a centrifugal pawl carried by the drum, a rotatable member provided with a 25 30 ratchet arranged to be engaged by said pawl when the drum rotates at high speed and a pair of spaced projections, and a pair of coiled springs mounted in the groove, each spring being arranged between one of said abutments and one of said 35 40 45
